UNITED STATES PATENT OFFICE.

ALLEN E. SNYDER AND MOSES SNYDER, OF BOWMANSTOWN, PENNSYLVANIA.

TRAIN CONTROL.

Application filed July 29, 1921. Serial No. 488,459.

To all whom it may concern:

Be it known that we, ALLEN E. SNYDER and MOSES SNYDER, citizens of the United States, residing at Bowmanstown, in the county of Carbon and State of Pennsylvania, have invented new and useful Im-

5 provements in Train Controls, of which the following is a specification.

This invention relates to train controlling mechanism and more particularly to means for automatically arresting the further travel of a locomotive or train operating over a railroad when a danger condition

Figure 2—is a side view of the same and looking towards the left of the preceding figure.

Figure 3—is a detail view of the governor mechanism; and,

Referring more particularly to the views 60 the numeral 10 designates a fragmentary portion of a rail-tie or road bed and 11 one of the rails over which travels the bogie wheel 12—conveniently one of the pony 65 truck bogies—supported by an axle in the well known way by a journal box 13 from the pony truck 14, said parts forming no

part of our invention and being simply referred to for a better understanding thereof.

According to our invention we attach to the under-part of the pony-truck 14 a laterally disposed bar or support 15 of channel cross-section which serves as a base on which the mechanism now to be described is 75 mounted. Securely clamped or attached on the support 15 as by bolts or set-screws 16 is a frame or pedestal 17 having an upstanding tubular bearing 18 and a spaced stand-

ard 19 to the latter of which is fixed a 80 stub-axle 20 by means of a screw 21. This stub-axle 20 serves as a journal for a belt pulley 22 having formed integral therewith a bevel gear 23, and said belt pulley 22 is

driven by means of a belt 24 from one of the 85 locomotive axles—not shown—but as will be clearly understood by those acquainted with the art to which this invention appertains.

Rotatably mounted in the aforesaid tubular bearing 18 by means of a sleeve 25 support-

90 ed at its lower end on an anti-friction washer 26 and ball bearing 27 is a

shaft 28 having keyed or otherwise secured thereon a bevel gear 29 in mesh with the

aforesaid gear 23. Integral with the upper 95

end of the shaft 28 there are provided ears

30 between which are pivotally mounted

governor balls 31 connected by links 32 with

a vertically slid able sleeve 33 feathered on

said shaft 28 by a key or the like 34. The 100

sleeve 33 is in turn provided at its lower

part with a loose collar 35 having laterally

projecting pintles 36 engaging in slots 37

in the yoked portion 38 of rockable lever

39 fulcrumed at 40 on an upstanding lug 105

41 provided for the purpose on the aforesaid

spaced standard 19. This rockable lever 39

is fitted at its inner end with an adjustable

balance weight 42 and is extended outwards

to project through a slot 43 in a plate frame 110

15 The primary object of my invention is to provide a locomotive with a mechanically actuated mechanism adapted to be tripped by electrically controlled means located at the side of the railroad when a block or other signal is set at danger, said mechanically actuated mechanism when so tripped being adapted through appropriate connections to open the air valve and thereby apply the brakes.

25 A further object of my invention is to provide a simple and effective train controlling mechanism which will arrest the movement of a locomotive or train whenever a danger condition is imminent by automatically applying the air brakes.

Still further this invention aims to provide a novel train controlling mechanism which is simple in construction, easy to manufacture and install, not liable to get out of order, whilst it can be readily applied to either steam, electric or otherwise self-propelled locomotives and trains.

With the foregoing and other objects in view as will become more apparent as this description proceeds the invention consists essentially in the novel features of construction, combinations and arrangements of parts hereinafter fully described and more specifically defined by the appended claims.

5 In the further disclosure of the invention reference is to be had to the accompanying sheets of explanatory drawings constituting a part of this specification, and in which like characters of reference designate the same or corresponding parts in all the views.

Figure 1—is an elevation of our improved train controlling mechanism, parts being broken away or in section for a clearer understanding of the underlying structure.

2

or member 44 conveniently supported by bracings 45 from the pony-truck frame 14, and said plate frame or member 44 is provided with vertical guides 46 in which is 5 adapted to be reciprocated a slide 47 with which co-operates the free end 39^a of the above referred to rockable lever 39. Pivoted pendulum fashion by a pin or stud 48 on the aforesaid slide 47 is a rockable or 10 trip-arm 49 which when in operative position—as later on explained—serves to effect the braking or retardation of the locomotive or other traveling vehicle, and said trip-arm 49 is appropriately fashioned with the 15 lower end tapered as shown in Fig. 2 to provide a suitable contacting surface. The upper part of the aforesaid trip-arm 49 is longitudinally slotted at 50 and passing therethrough in a substantially horizontal plane 20 is a rod or bar 51 having a medial flattened portion 52, and to one end thereof is pivotally connected a control rod 53 which through appropriate connections serves to open and close the engineer's primary air-braking valve mechanism—not shown—as 25 later on more particularly set forth. Pivoted at 54 on the opposed end of the rod or bar 51 is the upturned end or angled portion 55 of a bar 56 journaled in the plate 30 frame 44 and a bearing or journal 57 provided for the purpose on the aforesaid standard 19, the inner end of this bar 56 being fitted with one or more forked prongs 58 having operative connection with a sleeve 35 59 on the aforesaid vertical shaft 28 and in normally spaced relation below the sleeve 33 thereon. From the foregoing it will be readily seen that when the trip-arm 49 encounters or strikes any impediment in its 40 path of travel as later on explained it will be swung into the position shown by the dotted lines in Figure 2, which movement through the connections just described will partially turn the bar 56 about its longitudinal axis and raise the sleeve 59 by means 45 of prongs 58 into contact with the lower end of the sleeve 33.

In combination with the mechanism hereinbefore described we arrange in requisite 50 positions at that side of the rail 11 over which hangs the trip arm 49 a box-like casting 60 having an opening in its upper end through which is adapted to be automatically raised and lowered a plunger block 61. 55 From the foregoing description it will be readily understood that as the locomotive or train travels along the belt pulley 22 will be driven proportionally to the speed thereof by means of the belt 24, and as a 60 result of said rotation the gears 23, 29 will drive the shaft 28 whereby the governor balls 31 are relatively expanded or contracted. In the former case it will be apparent that as the governor balls 31 are 65 expanded the links 32 will draw the sleeve

33 upwards and thereby rock the lever 39 on its pivot or fulcrum 40, whereupon the slide 47 will move downwards carrying with it the trip-arm 49. Should the driver of the locomotive or train by inadvertence or 70 accident pass the signal or semaphore 71 set at "danger" it will be obvious that the trip arm 49 will strike the plunger block 61 and thus rock said trip-arm 49 on its pivot pin 48 to the position shown by dotted lines 75 in Figure 2, and through the engagement of said arm 49 with a pin 87 on the rod or bar 51 will move the control rod 53 to open the primary or engineer's air brake control valve. At the same time it will be seen that 80 the bar 56 will have been partially turned and the sleeve 59 raised into engagement with the underside of the sleeve 33. Instantly the air brakes are applied as set forth it will be obvious that the speed or 85 travel of the train and locomotive will be arrested and as a result the governor balls 31 will fall by gravity and return the parts 39, 49, and 56 to their normal positions as 90 will be clearly apparent to those acquainted with the art to which our invention appertains. As the balls 31 fall, the sleeve 33 is depressed by means of the links 32. The sleeve 33 in turn depresses the collar 59 which has been raised by reason of the displacement of the arm 49 by the obstacle 1, and the air brake valve is closed due to the 95 rotary motion imparted to the member 56.

From the foregoing description it will be readily seen that by our invention we have 100 provided an extremely effective and easily constructed train control whereby the braking of a locomotive and train is automatically effected in the event that the engineer should pass a danger signal by inadvertence, 105 accident or mistake.

Whilst there has been described and shown the best form of our invention at present known to us it will be obvious that the same is susceptible of considerable variation 110 and it is hereby intended to include all such reasonable changes and other combinations thereof as fairly fall within the scope of the appended claims.

Having described our invention, what we 115 claim as new and desire to secure by Letters Patent is:

1. In a train controlling mechanism the combination with a rotating axle thereof and the primary air brake valve, of a ball 12 governor mechanism comprising a pedestal having a vertical bearing and a spaced standard, a shaft journaled in said vertical bearing, governor balls pivoted at the upper end of said vertical shaft, a non-rotatable sleeve slidable on said shaft and connected with the governor balls, means for revolving said shaft by the aforesaid rotating axle, a pendulum trip arm adapted to be lowered and raised with the acceleration 13

- and retardation respectively of the governor balls, means associated with the pendulum trip arm for returning said arm to inoperative position, said means comprising a pivoted bar associated with said non-rotatable sleeve, and means associated with said trip arm to operate said primary air brake valve.
2. In a train controlling mechanism the combination with a rotating axle thereof and the primary air brake valve, of a ball governor mechanism comprising a pedestal having a vertical bearing and a spaced standard, a shaft journaled in said vertical bearing, governor balls pivoted at the upper end of said vertical shaft, a non-rotatable sleeve slidable on said shaft and connected with the governor balls, means for revolving said shaft by the aforesaid rotating axle, a frame having vertical guides thereon, a slide movable in said guides, a depending trip arm pivotally mounted on said slide, means connecting said slide with the aforesaid sleeve on the vertical shaft whereby the depending arm is lowered and raised with the acceleration and retardation respectively of the governor balls, a pivoted bar journaled in the last mentioned frame and the standard, said bar having an angled outer end, a sleeve on the governor shaft having operative connection with the inner end of said pivoted bar, and a transversely disposed link-bar passing through a slot in the upper end of the depending trip arm having pivotal connection at one end with the angled end of the pivoted bar.
3. In a train controlling mechanism the combination with a rotating axle thereof and the primary air brake valve, of a ball governor mechanism comprising a pedestal having a vertical bearing and a spaced standard, a shaft journaled in said vertical bearing, governor balls pivoted at the upper end of said vertical shaft, a non-rotatable sleeve slidable on said shaft and connected with the governor balls, means for revolving said shaft by the aforesaid rotating axle, a frame having vertical guides thereon, a slide movable in said guides, a depending trip arm pivotally mounted on said slide, a lever fulcrumed on the aforesaid standard having latching engagement beneath the vertically movable slide and operative connection with the sleeve connected to the governor balls whereby the trip arm is lowered and raised with the acceleration and retardation respectively of the governor mechanism, and means associated with and actuated by the pendulum trip arm for automatically operating the said air brake valve.
4. In a train controlling mechanism the combination with a rotating axle thereof and the primary air brake valve, of a ball governor mechanism comprising a pedestal having a vertical bearing and a spaced standard, a shaft journaled in said vertical bearing, governor balls pivoted at the upper end of said vertical shaft, a non-rotatable sleeve slidable on said shaft and connected with the governor balls, means for revolving said shaft by the aforesaid rotating axle, a frame having vertical guides thereon, a slide movable in said guides, a depending trip arm pivotally mounted on said slide, means connecting said slide with the aforesaid sleeve on the vertical shaft whereby the depending arm is lowered and raised with the acceleration and retardation respectively of the governor balls, a pivoted bar journaled in the last mentioned frame and the standard, said bar having an angled outer end, a sleeve on the governor shaft having operative connection with the inner end of said pivoted bar, and a transversely disposed link-bar passing through a slot in the upper end of the depending trip arm having pivotal connection at one end with the angled end of the pivoted bar.
5. In a train controlling mechanism the combination with a rotating axle and the primary air brake valve, of a ball governor mechanism comprising a vertical bearing and a spaced standard, a shaft journaled in said bearing, governor balls pivoted at the upper end of said shaft, a slidable sleeve on said shaft connected to the governor balls, a frame having vertical guides, a slide received in said guides, a depending trip arm pivotally mounted on said slide, a pivoted bar attached to said slidable sleeve and supporting said slide, whereby the slide is lowered or raised, means associated with said trip arm for opening the brake valve, and means for automatically closing the brake valve.
- In testimony whereof we affix our signatures.

ALLEN E. SNYDER.
MOSES SNYDER.
